UNITED STATES PATENT OFFICE.

AUGUSTUS WILLIAM GETCHELL, OF CLEVELAND, OHIO, ASSIGNOR OF ONE-EIGHTH TO THEODORE W. ENSIGN, OF SAME PLACE.

CAR-TRUCK.

SPECIFICATION forming part of Letters Patent No. 333,623, dated January 5, 1886.

Application filed August 28, 1885. Serial No. 175,590. (No model.)

To all whom it may concern:

Be it known that I, AUGUSTUS WILLIAM GETCHELL, of Cleveland, in the county of Cuyahoga and State of Ohio, have invented certain new and useful Improvements in Roller-Trucks for Railway-Cars, of which the following is a specification.

This invention relates to trucks for railway-cars, and has for its object to provide an anti-friction truck constructed and arranged in such a manner that the car is carried on the rails on rollers, which do not turn on axles or journals, require no oiling, whereby a car is easily started and kept in motion.

15 The principle upon which this invention is based is that large and heavy bodies are easily moved on rollers, require less power to put in motion, and the momentum thus easily gained enables a car to be easily kept moving.

20 This method is especially adapted to extremely heavy loads.

In the accompanying drawings, Figure 1 is a side elevation of lower part of a car having my improved roller-truck attached, with side 25 plate removed to show position of rollers. Fig. 2 is a cross-section on line 2 2 of Fig. 1. Fig. 3 is a perspective view in cross-section, showing a modification in arrangement of rollers, showing opposite rollers united by axles 30 and dispensing with inside plates. This modification may be adopted on narrow-gage tracks; but the plan shown in Figs. 1 and 2 is preferable.

To the under side of the body of the car A 35 are firmly attached depending plates B B, the inside faces of which have longitudinal grooves C C, and between said plates B are firmly bolted beams D midway between the said grooves. Said beams have their lower sides inclined at 40 the ends, as seen in Fig. 1, for a purpose hereinafter shown. E are rollers having an annular flange on one end, and are provided with short journals on each end, which run along in the aforesaid grooves C in the plates B.

The purpose of these grooves and the journals 45 on the rollers is not for the rollers to turn upon, except at the extreme points of the beams, but for the purpose of keeping the rollers in place and preventing their dropping out of the truck. A groove, d, is made in the sides 50 of the beam for the flanges of the rollers to run in as they travel along on the upper and lower sides thereof. The rollers run on the track in like manner to other car-wheels.

In Fig. 3 the rollers are seen united in pairs 55 by axles, in which case the inside plates may be dispensed with.

The operation of this truck is as follows: The rollers beneath the beam are free to roll between the beam and the track, the groove 60 in the plates being made wide enough so that the journals of the rollers do not touch. Thus the car rolls along on the rollers. When, however, the rolls reach the rear end of the beam and are pushed up the incline, they roll 65 on their journals in the grooves, and are thus carried around the point of the beam, up onto the top surface of the beam, and are easily rolled along thereon, and successively drop off from the forward point of the beam, descending 70 the incline, and take their places underneath the beam, thus continuously and successively providing a means of propelling the car on the track on rollers. The rolls are not placed close enough to interfere with one another, but roll along independently. Neither do they bind by twisting, for their ends are 75 broad enough to prevent twisting.

Having described my invention, I claim—

The combination, with the car A, of the 80 truck consisting of the grooved plates B B, beam D, and flanged rollers E, constructed and arranged to operate substantially as and for the purpose specified.

AUGUSTUS WILLIAM GETCHELL.
